UNITED STATES PATENT OFFICE

REUBEN S. TICE, OF MONTEREY, AND ARTHUR L. HOLCOMB, OF SAN JOSE, CALIFORNIA

RELAY

Application filed February 25, 1929. Serial No. 342,652.

The present invention relates to improvements in relays and more particularly constitutes a further development of the invention shown in Patent No. 1,681,446, to Reuben S. Tice.

The object of the invention shown in the latter patent was to provide a thermostatically controlled circuit arranged in such a manner that electromagnets responsible for the closing and opening of a heating circuit and subject to control by a thermostatic element would become deenergized immediately after having become active, so that the thermostatic element could move away from its contact under the influence of changed conditions without causing any arcing.

While the present invention serves substantially the same purpose, it is intended to introduce a novel relay particularly adapted for this particular circuit.

Further objects and advantages of our invention will appear as the specification proceeds.

The preferred form of our invention is illustrated in the accompanying drawing, in which

Figure 1 shows a wiring diagram explaining the circuit;

Figure 2 is a side elevation of our relay;

Figure 3, a top plan view thereof.

Figure 4, a fragmentary view showing a modified form of contact mounting.

While we have shown only the preferred form of our invention, it should be understood that various changes or modifications may be made within the scope of the claims hereto attached without departing from the spirit of the invention.

The general idea of our invention may be best understood by reference to Figure 1, from which it appears that the main circuit comprising the wires 1 and 2 has a suitable heating device 3, or any other current-consuming device, and a switch 4 connected therein.

The switch 4 comprises two spring elements 6 mounted in spaced relation on a base 7 and the armature 8 of an electromagnet 9. The latter is mounted on the bottom member 11

of a rectangular frame 12 and between the two contact members 6, while the armature is hinged to one end wall of the frame, as shown at 13, and extends from there over the armature and beyond the same, being formed with a cross piece 14 adapted to interconnect the two contacts 6 when the armature is attracted by the electromagnet. Normally, a spring 16 holds the armature in an inactive position.

The electromagnet 9 forms part of a branch circuit shunted across the main switch and comprising the wire 17, the stationary contact 18, a movable contact 19 and the wire 21. The movable contact 19 forms part of a thermostat specifically designed for the present purpose, but adapted for other purposes, and this thermostat, roughly indicated at 22, is described and claimed in a co-pending application, Serial No. 342,651, filed February 25, 1929. For the present purposes, it is sufficient to say that the thermostat comprises two bimetallic spirals 23 and 24 having their loose ends interconnected under tension, so that the connecting piece carrying the contact 19 snaps beyond the center line in one direction or the other under the influence of changes in temperature and establishes contact either with the stationary contact 18, or with another contact shown at 26. It will be seen that when the points 18 and 19 contact, the magnet 9 becomes energized, attracts the armature 8 and thereby closes the main switch.

The closing of the main switch withdraws practically all the current from the branch circuit, so that there is no arcing when the points 18 and 19 separate.

Immediately upon actuating the armature 8, the electromagnet 9 therefore becomes practically deenergized, and in order to hold the armature 8 in the switch-closing position, we provide a latch element 27 pivoted to the bottom member of the frame, as shown at 28, and urged by a spring 29 into locking engagement with the armature 8. The latch member 27 also constitutes an armature for a second electromagnet 31 mounted on the second end wall of the frame 12 and is withdrawn from its locking engagement with the armature 8 when the electromagnet 31 is ener-

gized. This latter electromagnet forms part of a circuit including the wire 32, the stationary contact 26, the movable contact 19 and the wire 21. It will be noted that this second branch circuit is in series with the main switch and is shunted across the heating element 2. When this branch circuit becomes active, the electromagnet 31 withdraws the latch member 27 from its switch-locking position and allows the main switch to open. It will be noted that immediately upon the opening of the main switch, the current ceases to flow in the second branch circuit containing the electromagnet 31, since this branch circuit is in series with the main switch.

The operation of the device will be readily understood from the foregoing description.

When the temperature drops below a certain predetermined degree, the thermostat 20 causes the points 18 and 19 to contact, whereby the electromagnet 9 is energized, the armature 8 attracted and the main switch closed, which causes the heater to become active. The closing of the main switch withdraws 25 practically all the current from the branch circuit, so that the electromagnet 9 immediately becomes deenergized, while the latch member 27 holds the armature 8 in switch-closing position. As the temperature rises 30 beyond a predetermined degree, the thermostat causes the point 19 to separate from the point 18 and to snap over to point 26, thereby closing the second branch circuit. It should be noted that no arcing will be caused by the 35 snapping over of the thermostat contact, since at the time it occurs, there is no current in the branch circuit containing the electromagnet 9. The second branch circuit is now closed, and the electromagnet 31 becomes energized and draws the latch member 27 away from its locking position, thereby allowing the armature 8 to open the main switch under the influence of the spring 16. It will be noted again that immediately after performing the task of opening 40 the main switch, the branch circuit loses its current, since it is in series with the main switch. Therefore, as soon as the temperature has cooled down to a predetermined degree again for causing the thermostat contact 45 50 to snap over to the contact 18, this change again will be effected without any arcing at the contacts.

A modified form of mounting for the contact member 6 is shown in Figure 4.

In this form, the contact member consists of a straight strip of spring material having its rear end secured to the top of a block 36 60 of conducting material by means of screws 37, the block being secured to the base 7 by means of screws 38 and being formed with a perforation 39 into which the lead wire 41 is passed. A screw 42 threaded into the block 65 from the top holds the wire 41 in place.

We claim:

1. In a relay of the character described, a frame including a base member and two end members, an electromagnet mounted on the base member, a circuit having two contacts on opposite sides of the electromagnet, an armature hinged to an end member so as to lie over the electromagnet and having means bridging the two contacts when the armature is attracted and means normally urging the armature into inactive position, a latch member hinged to the base and adapted for locking engagement with the armature when the latter moves into active position and a second electromagnet mounted on the other 70 end member and adapted to withdraw the latch member from locking position when the second electromagnet is energized.

2. In a relay of the character described, a main circuit containing a current consuming device and a switch including as movable member an armature, a branch circuit shunted across the switch and containing an electromagnet in operative proximity of the armature for closing the switch when energized, a latch member for locking the armature in switch-closing position, a second branch circuit in series with the switch and shunted across the current-consuming device and having an electromagnet mounted relative to the latch member for withdrawing the same from locking position when the second electromagnet is energized and a thermostatic control element forming part of both branch circuits and adapted to close either 90 95 while opening the other under predetermined conditions.

3. In a relay of the character described, a frame including a base member, two end members and a top member, an electro-magnet mounted on the base, an armature hinged to one of the end members so as to horizontally surmount the electro-magnet, a second electro-magnet secured to the other end member, and a second armature hinged relative 105 110 to the second electro-magnet and adapted to serve as latch for the first armature, the armatures being arranged to cooperate with the frame members in providing paths for the magnetic flux when the respective electro-magnets are energized.
